UNITED STATES PATENT OFFICE

SIMON J. LONERGAN, OF LA PORTE, INDIANA

DESIGN FOR A WATER HEATER CASING OR LIKE ARTICLE

Application filed September 17, 1932. Serial No. 44,982. Term of patent 7 years.

To all whom it may concern:

Be it known that I, SIMON J. LONERGAN, a citizen of the United States, residing at La Porte, in the county of La Porte and State of Indiana, have invented a new, original, and ornamental Design for a Water Heater Casing or Like Article, of which the following is a specification, reference being had to the accompanying drawing, forming part thereof.

Fig. 1 is a perspective view of a water heater casing showing my new design.

Fig. 2 is a top plan view thereof.

I claim:

The ornamental design for a water heater casing or like article, as shown.

SIMON J. LONERGAN.
